UNITED STATES PATENT OFFICE.

ARTHUR MIDDLETON ROSE, OF YONKERS, NEW YORK.

DESIGN FOR CARPET.

SPECIFICATION forming part of Design No. 26,057, dated September 15, 1896.

Application filed August 11, 1896. Serial No. 602,456. Term of patent 3½ years.

To all whom it may concern:

Be it known that I, ARTHUR MIDDLETON ROSE, a citizen of the United States, residing at the city of Yonkers, in the county of Westchester and State of New York, have invented and produced a new and original Design for a Carpet or other Fabric, of which the following is a specification, reference being had more particularly to the accompanying drawing, illustrating the same and forming part hereof.

The leading feature of my design is bouquets of roses and floral garlands upon a ground of scrollwork and leaf forms.

My design may be expressed in various colors or combinations of colors and applied to ingrain, Brussels, Wilton, velvet, or other carpeting.

In the drawing, a is the body, b the border, and a b the complete carpet.

c are bouquets of flowers.

d are floral garlands.

e is scrollwork, and f are leaf forms.

What I claim as my invention, and desire to secure by Letters Patent, is—²⁵

1. In a design for a carpet, the body a, substantially as shown.
2. In a design for a carpet, the border b, substantially as shown.
3. The design for a carpet consisting of the body a, and border b, substantially as shown.

In testimony whereof I have hereunto signed my name in the presence of two witnesses.

ARTHUR MIDDLETON ROSE.
